UNITED STATES PATENT OFFICE

167,719

REFRIGERATOR UNIT FOR AN OXYGEN TENT

Robert J. Reading, Darien, Conn., assignor to
O. E. M. Corporation, a corporation of Delaware

Application December 28, 1951, Serial No. 17,842

Term of patent 14 years

(Cl. D83—1)

To all whom it may concern:

Be it known that I, Robert J. Reading, a citizen of the United States and residing at Darien, in the county of Fairfield and State of Connecticut, have invented a new, original, and ornamental Design for a Refrigerator Unit for an Oxygen Tent, of which the following is a specification, reference being had to the accompanying drawings, forming part thereof, and in which:

Fig. 1 is a front perspective view of the refrigerator unit for an oxygen tent, showing my new design, and

Fig. 2 is a rear perspective view thereof.

I claim:

The ornamental design for a refrigerator unit for an oxygen tent, substantially as shown.

ROBERT J. READING.
